UNITED STATES PATENT OFFICE.

WILLIAM MORTENSEN, OF MONTREAL, QUEBEC, CANADA.

BUILDING CONSTRUCTION.

1,115,088.

Specification of Letters Patent.

Patented Oct. 27, 1914.

Application filed November 8, 1913. Serial No. 799,909.

To all whom it may concern:

Be it known that I, WILLIAM MORTENSEN, a citizen of the United States of America, and resident of 782 St. Urbain street, in the city of Montreal, Province of Quebec, in the Dominion of Canada, have invented certain new and useful Improvements in Building Construction; and I do hereby declare that the following is a full, clear, and exact description of the same.

The invention relates to improvements in building construction as described in the present specification and shown in the accompanying drawings that form part of the same.

The invention consists essentially of the novel construction of a fireproof building, whereby the supporting parts are light and strong as well as convenient in the arrangements they provide.

The objects of the invention are to construct a fireproof building at a low cost, to eliminate as far as possible the use of false work, to construct a floor and ceiling of short and light slabs at the same time using a moderate amount of supporting steel, to devise a structure which has natural conduits for light, heat and the like without affecting the strength, and generally to provide a simple, and efficient building construction.

In the drawings, Figure 1 is a cross sectional view of a supporting column. Fig. 2 is a side view of a steel trussed concrete girder. Fig. 3 is a cross sectional view of a main girder showing the lighter floor and ceiling trusses extending laterally therefrom. Fig. 4 is a side view of the light floor and ceiling trusses as applied to the I-beam girder supports in a building of steel skeleton construction.

Like numerals of reference indicate corresponding parts in each figure.

Referring to the drawings, 1 are angle bars of structural steel, and forming the corner posts of the skeleton structure in the vertical columns that support the horizontals, said angle bars having the section 10 projecting inwardly in pairs in alinement respectively. The bars 1 are joined preferably by lattice bars not here shown, and extend upwardly from the concrete foundation 11, said skeleton upright formed by the bars and lattice being subsequently submerged in the concrete A after the horizontals have been attached thereto.

2 are horizontal bars of structural steel having their sections 12 extending inwardly, that is to say toward one another, and the other sections rigidly secured to the inwardly extending sections 10 of the angle bars 1, said bars 2 forming the upper horizontals of the skeleton of the truss structure B.

4 are angle bars having the sections 14 pointing inwardly toward one another and their other sections rigidly secured to the sections 10 of the angle bars 1 and forming the lower horizontal bars of the skeleton truss structure B.

3 are lattice bars extending from the angle bars 2 to the angle bars 4 and completing the skeleton structure B.

7 are angle bars forming the upper horizontals of the light truss T, the upright sections 17 being back to back and slightly spaced one from the other, while the other sections of said angle bar 7 are secured on an angle bar 2.

5 are the lower angle bars of the truss T immediately under the angle bars 4 having their upright sections 15 back to back and slightly spaced, said lower angle bars 5 being rigidly joined to the angle bars 7 by the lattice bars 6.

6 are ceiling slabs of terra cotta or such like material having the reduced ends 25 forming dove-tailed slots for the slabs W, the said reduced ends 25 resting on the upper side of the angle bars 5, and said slabs W closing in said angle bars and supporting the cement or concrete that flows through the space between said angle bars 5.

g are the floor slabs having reduced ends 26 resting on the angles 7, said slabs being 95 suitably spaced apart by the said angles 7, forming a passage for pouring grout which may be of concrete, cement or any suitable plastic compound subsequently brought to its consistent state.

C are slabs supported on the ceiling slab b, and abutting the extreme edges of the angle bars 7 and spaced and secured by the bolts 8, said slabs C inclosing the lattice bars 6 and bolts 8 and also containing therebetween the grout h, which has been previously poured between the angles 7, thereby completing the light truss. The ceiling slabs extend under the truss structure B and support the slabs g¹, which at their upper end 110 abut the floor slabs g, consequently a chamber is formed for containing the grout G,

which completely submerges the angles 2 and 4 and lattice bars 3, and also the ends of the horizontals, thus forming the main concrete girders for the support of the light 5 trusses T. The vertical columns supporting the main concrete trusses are preferably inclosed by the slabs or blocks O, which form part of the permanent structure. The main girders are pierced in the spaces between the 10 light trusses to form continuous conduits as indicated at f.

In Fig. 4, the light truss T is shown as supported on the I-beam 9, otherwise it is precisely the same.

15 The great advantage of this invention is that in using the light trusses as described, instead of the customary I-beam structure, the same weight of material will support a very much greater load, therefore the trusses 20 can be placed much closer together without extravagance in the use of steel. This construction also enables the builder to use a short slab for the floors and ceilings as the flanges of the I-beams are not so well suited 25 for laying slabs on.

The method of fireproofing in this structure is entirely different from what has been heretofore known, as in this truss the concrete is poured between the angles of the 30 top chord and this is both an easier and better method than commonly used and completely submerges all the structural steel.

What I claim is:—

35 1. In building construction, columns of structural steel and grout, main girders of structural steel, secured to said columns, and grout and light trusses formed of upper

angle bars of structural steel secured to said main girder, steel having the upright sections back to back and spaced and lower sections similarly arranged below, joined by lattice bars and inclosed by longitudinally arranged slabs secured by spacing bolts and forming a chamber and grout in said chamber, floor slabs having reduced ends resting on the horizontal sections of said upper angles, and ceiling slabs having reduced ends resting on the horizontal sections of said lower angles.

2. In building construction, columns of structural steel angles, lightly latticed, and concrete; main girders of structural steel angles, latticed by flat bars or angles, and concrete, and secured to said columns; and light trusses secured to said girder, having upper and lower chords of structural steel angles placed back to back and inner flanges turned upright, joined by lattice bars or angles and inclosed by longitudinally arranged slabs secured by bolts and forming a chamber, and grout in said chamber; floor slabs having reduced ends resting on the horizontal flanges of said upper chord angles, and ceiling slabs having reduced ends resting on the horizontal flanges of the said lower chord angles.

Signed at the city of Montreal, Province of Quebec, Canada, this 31st day of October, 1913.

WILLIAM MORTENSEN.
